Application March 17, 1933, Serial No. 661,319

19 Claims.

(CL 93—6)

This invention relates to a packaging machine.

One object of the invention is to provide a novel and improved packaging machine which is adapted to close and seal an open end of a fibrous container, such as a carton or paper bag, in a novel and superior manner to produce an efficiently sealed container.

Another object of the invention is to provide a novel and improved packaging machine in which provision is made for preparing a moisture-proof container to remove the moisture-proof coating from the marginal portions of the inner surfaces of the body of the bag at an open end thereof, and in which provision is made for closing and adhesively sealing the open end of the bag with the paper to paper contact extending across the end of the bag.

A still further object of the invention is to provide a novel and improved machine for making an open end container and thereafter closing and adhesively sealing the open end with the paper to paper contact extending entirely across the end of the bag.

Another object of the invention is to provide a novel and improved method for making an efficiently closed and sealed container.

With these general objects in view, the invention consists in the machine, in the method and in the various structures, arrangements and combinations of parts, all as hereinafter described and particularly defined in the claims at the end of this specification.

In the drawings illustrating a packaging machine embodying the different features of the invention, Fig. 1 is a side elevation of the machine; Fig. 2 is a sectional view taken on the line 2—2 of Fig. 1, viewed in the direction of the arrow, with the upper portion of the container forming mechanism omitted; Fig. 3 is a plan view of a portion of the machine shown in Fig. 2; Figs. 4, 5 and 6 are details to be referred to of mechanism for removing the paraffin wax or other moisture-proof coating to prepare the container for the subsequent sealing operations to be described; Fig. 7 is a sectional detail of the filling mechanism, taken on the line 7—7 of Fig. 1; Fig. 8 is a similar view taken on the line 8—8 of Fig. 1 and illustrating the mechanism for applying the adhesive and folding the top of the container to produce the improved closed and sealed container; Figs. 9 and 10 are diagrammatic views in side and front elevation illustrating the operation of a portion of the closing and sealing mechanism; Fig. 11 is a sectional detail taken on the line 11—11 of Fig. 1, illustrating the mechanism for

folding down the previously sealed top of the bag; Fig. 12 is a sectional detail taken on the line 12—12 of Fig. 1, illustrating the mechanism for folding in the end tabs of the lining; Fig. 13 is a detail in plan illustrating the mechanism for rotating the carton holding pockets, as will be described; Figs. 14 and 15 are sectional details on the lines 14—14 and 15—15 respectively of Fig. 13; Figs. 16 and 17 are details and plan in elevation respectively of the package pusher for transporting the container with the liner therein; Fig. 18 is a sectional detail taken on the line 18—18 of Fig. 1; Figs. 19 and 20 are perspective views illustrating the mechanism for folding and sealing the flaps of the outer carton; Fig. 21 is an end view of the mechanism shown in Fig. 20; Fig. 22 is a sectional detail taken on the line 22—22 of Fig. 1 and illustrating the mechanism for pressing the closed and sealed top of the carton; Fig. 23 is an end view illustrating the mechanism for ejecting the completed cartons from the machine; Figs. 24 through 33 are diagrammatic views illustrating the successive steps in the production of the present closed and sealed lined carton; and Fig. 34 is a diagrammatic view illustrating the modified form of mechanism for removing paraffin or other coating from the paper web.

In general, the present invention contemplates a packaging machine for producing an improved and efficiently sealed container. The container may comprise a paper bag or a carton, and, as herein shown, the machine is adapted to produce a lined carton, that is, a carton provided with an inner paper container or bag, and provision is made in the illustrated machine for making the inner container or bag from a roll supply of bag forming material, introducing the formed inner container or liner into a carton and subsequently filling the inner container. Thereafter provision is made for folding and sealing the mouth of the liner or inner container in a manner such as to provide an efficiently closed and sealed container or liner and for subsequently folding the sealed portion down into a position to permit the flaps of the outer container or carton to be folded and sealed to produce a completely closed and sealed lined package. In some instances it may be desirable to utilize a moisture-proof material for the production of the liner or inner container and in practice such material may comprise waxed or paraffin coated paper, and when such waxed or paraffin coated paper is used for the construction of the container, provision is made for removing the moisture-proof coating

such as the paraffin from the inner portion of the mouth of the bag or container so that during the subsequent folding and sealing operations a paper to paper contact and seal may be produced, preferably extending entirely across the mouth of the bag or container.

While as herein shown the machine is designed to produce a lined package in which provision is made for removing paraffin or other moisture-proof material from the paraffin coated web from which the liner or inner package is produced, nevertheless in its broader aspects the invention may be embodied in machines for producing a unitary container which is closed and sealed in the improved manner whether or not moisture-proof material is used in the construction of the container.

Referring now to the drawings, and particularly to Figs. 1, 2, and 3 hereof, the illustrated machine is provided with an incoming conveyor 10 by which containers, preferably cartons open at their upper end, are delivered in succession to succeeding pockets 12 of carton holding members 14 mounted upon and forming a part of a rotatable spider 15. The latter is intermittently moved during the operation of the machine so that after a container has been introduced into a pocket, the pocket and the outer container are intermittently moved into a succeeding station in which the inner container or lining is introduced into the outer container held in the pocket. The lining or inner container is preferably formed from a supply of material contained in a supply roll 18 which is drawn off in the manner illustrated in Fig. 1 and conducted through suitable mechanism for forming a lining blank therefrom and subsequently folding the blank around the usual forming block 20 and folding and sealing the bottom flaps to form a container open at its top and closed at its bottom. The details of construction of the mechanism for forming the lining and for introducing it into the package may comprise that illustrated in the patent to Doble and Robinson, No. 1,247,238, to which reference may be made for a complete description thereof. Inasmuch as the details of this mechanism are well known and fully set forth in said patent, and of themselves constitute no part of the present invention, it is believed to be sufficient to state that, by the operation of the mechanism referred to, succeeding inner containers or linings are produced and introduced into the outer containers and which for convenience of description will be hereinafter referred to as cartons.

Reference is now made to Figs. 24 through 33 which illustrate diagrammatically the successive steps in the formation of the inner container or liner about the usual forming block illustrated in said Doble and Robinson patent, and from which it will be observed that after the liner has been introduced into the carton, the liner is arranged to project above the open upper end of the carton in a condition such as is illustrated in Fig. 28.

After the liner has thus been introduced into the carton, the next step in the operation of the machine comprises the intermittent movement of the spider with the lined carton from a position indicated in Fig. 3 at station A to the position indicated as station B, and provision is then made for transferring the lined carton from the pocket 12 at station B to a corresponding pocket 23 comprising a part of an endless conveyor 24 by which the lined cartons are successively moved

through a number of stations to be filled and closed and sealed as will be described. As illustrated, the transfer of the lined carton to the pocket 23 occurs while the pocket 23 of the conveyor 24 is at station No. 1 in the successive movements of the conveyor.

As herein shown, the mechanism for effecting the transfer of the carton from the pocket at station B to the aligned pocket 23 of the endless conveyor at station 1, and also the mechanism for intermittently moving the conveyor 24, operates in timed relation to the operation of the spider 15 and, as shown in Figs. 2 and 3, a cam shaft 30 for effecting the transfer of the carton is arranged to make one revolution at each cycle of operation of the machine corresponding to a quarter turn of the spider 15. As shown in Fig. 2, the cam shaft 30 is connected through a chain 32 and sprockets 33, 34 and through bevel gears 36, 38 to a one-revolution shaft 40 driven, as will be described, to make one revolution at each quarter turn of the spider 15. Provision is also made for operatively connecting the movement of the spider 15 with the movements of the endless conveyor 24 so that at each quarter turn of the spider an empty pocket 23 on the conveyor is brought into alignment to receive the carton being transferred from station B into the pocket at station 1. As shown in Fig. 2, the connections include a chain 42 and two sprockets 43, 44, the sprocket 44 being on a counter shaft 46 connected by bevel gears 47, 48 to the intermittently driven shaft upon which the spider 15 is mounted.

Referring now to Fig. 2, the cam shaft 30 is provided with a closed cam 50, and connection is made between the cam 50 and a package pusher 52 through a cam roll 53 on a cam arm 54 connected by a link 55 to a lever 56, and the lever 56 is connected to a block 58 on a rod 59 arranged to slide in bearings in a bracket member 60. The package pusher 52 is mounted upon and depends from the forward end of the rod 59 so that at each revolution of the cam 50 the package pusher is advanced to push the lined package from the pocket 12 at station B to the aligned pocket 23 at station 1 of the conveyor. As shown in detail in Figs. 2, 16 and 17, the package pusher 52 is constructed so that it may be moved by the package on its backward stroke and will be snapped into position behind the package by a spring 600 so that upon forward movement of the package pusher the package will be moved to the aligned pocket 23 at station 1 of the conveyor. As shown in Fig. 2, the package is carried from the pocket 12 by the belt 10 into a position to be engaged by the package pusher 52, as above described.

Referring now to Figs. 1, 3 and 7, during the continued operation of the machine the endless carrier 24 operates to intermittently advance the pockets 23 carrying the lined carton through an intermediate and idle station 2 to a filling station 3 where provision is made in the illustrated machine for filling the lined carton with goods, and while the details of the filling mechanism per se comprise no part of the present invention, for purposes of illustration a typical filling mechanism has been herein illustrated as including a hopper 60 provided with a measuring drum 62 having four measuring compartments 63 formed by partition members 64 and the measuring drum 62 is arranged to be rotated intermittently from a cam 66 through a cam roll 67 on a cam arm 68 forming one arm of a bell-crank, the second arm 69 of which is connected by a link 70 to an operating arm 72 secured upon the end of the shaft 75

74 upon which the partition members 84 are mounted, and connection is made between the shaft 74 and the arm 72 through a pawl 75 and ratchet 76 to thereby intermittently advance the 5 measuring drum a quarter turn at each revolution of the cam 86. The cam 86 is mounted upon the cam shaft 30 and is arranged to make one revolution at each cycle of operation of the machine.

10 After the package has thus been filled, the endless carrier operates to intermittently move it through an idle station 4 to a succeeding station 5 where provision is made for applying adhesive to the inside of the upper portion of the mouth of the liner and for thereafter moving outwardly the end portions of the mouth of the liner to bring the two halves of the mouth of the liner into contact and for pressing the same together to effectively provide a seal extending across the entire mouth of the inner bag or liner. As herein shown in Figs. 8, 9 and 10, the mechanism for accomplishing this result comprises a vertically reciprocating member 78 arranged to slide in a guideway in a bracket 80 and which is adapted to be moved into and from operative position through a closed cam 82 mounted upon the cam shaft 30 and through a cam roller 84 on a cam arm 85 connected by a link 86 to the upper end of the slide and arranged at the proper time in the operation of the machine to cause the operating member 78 to descend into engagement with the mouth of the inner bag or liner. The lower end of the operating member 78 is made of a width such as, and is also provided with inclined surfaces adapted, to engage the end portions 79 of the mouth of the inner bag or liner and to force the same outwardly as the operating member descends. The width of the lower portion of the operating member is such that when the parts are 40 in the position shown in Fig. 10, the mouth of the inner bag or liner will have been moved outwardly by the inclined surfaces to an extent such that the two opposite and intervening side portions 81 of the mouth of the inner bag or liner 45 contact with a gluing member 82 formed as an enlargement upon the operating member 78.

While the parts are in the position illustrated in Figs. 9 and 10, provision is made for pressing the two side portions 81 of the mouth of the liner into contact with the gluing member 83 to apply adhesive to the inside of the mouth of the liner and, as herein shown, two presser members 85, 86, preferably of rubber or other yieldable material and having depending curved portions adapted to contact with the neck of the liner below the portion being sealed, as shown in Figs. 8 and 9, are mounted upon slide members 87, 88 arranged to slide in bearings 89, 90 forming a part of the machine frame. The presser members 85, 86 are actuated by a spring 92 through mechanism including a lever 94, one arm 95 of which is provided with a segment 96 adapted to mesh with the similar segment 97 on a bell-crank 98 connected by a link 100 to one of the slide members 87. The second slide member 88 is connected by a similar link 101 to the corresponding arm 102 of a three-arm lever. One arm 94 of the three-arm lever is connected by a link 104 to a cam arm 105 provided with a cam roll 106 adapted to operate with an open cam 107 also mounted upon the cam shaft 30, and the movements of the slide members into operative position are effected by the spring 92, while the movement of the slide members from operative position are effected by 75 the cam 107, and as a result in the operation of

the machine the spring operates to exert a yielding pressure which is utilized together with the yieldable character of the presser members to effectively press the portions of the mouth of the liner to be sealed into efficient contact with the 5 glue applying member 82 to thereby apply sufficient adhesive to the portions of the mouth of the bag to be sealed so that when the operating member is raised through the operation of its cam and through the linkage above described, the 10 spring actuated presser members operate to yieldingly press the two opposite sides of the mouth of the bag into contact and to provide a complete seal across the entire mouth of the liner. During the upward movement of the operating member 15 the glue applying member 83 is brought between a pair of yieldable glue rolls 108, 109 fed from supply rolls 110, 111 rotatable within glue pans 112, 113, as illustrated in Fig. 8, to thereby supply 20 fresh glue to the operating member.

During the movement of the package into the station at which the mouth of the liner is to be sealed in the manner above described, provision is made for bending outwardly and holding the side flaps at the top of the carton or outer container, and which would otherwise interfere with the operation of the adhesive applying and sealing mechanism. Referring now more particularly to Figs. 24 through 33 which illustrate diagrammatically successive steps in the formation of the 30 liner, it will be observed that after the liner has been formed and introduced into the carton and at the point in the operation of the machine where the carton and liner move into station 5, the carton and liner are in a condition such as is illustrated in Fig. 28, and during the movement of the carton into station 5, the two side flaps of the carton are brought into contact with guide and retaining rails 116, 117 arranged to bend such flaps outwardly and to hold them in a substantially horizontal position, such as is illustrated in Figs. 8, 9 and 10, and out of the path of the reciprocating sealing and pressing members 85, 86 above described. During the continued movement of the carton into the next station at which provision is made for folding down the top or sealed portion of the liner, and during the operations at this station, the side flaps of the carton continue to be held down out of the way by the guide rails 116, 117 which are arranged to extend slightly 50 beyond this station.

Referring now to Fig. 11, the mechanism therein illustrated for folding down the top or sealed portion of the liner includes two plate-like folding members 120, 121. Both folding members are 55 pivotally mounted upon the end of arms 122 being free to yield upwardly, as shown in Fig. 11, and arranged to be held downwardly against stop screws 124 by coiled springs 125, 126 arranged as illustrated. With this construction, during the 60 inward movement of the folding plates 120, 121, provision is made for enabling them to yield upwardly during both their inward and outward movement to prevent the plates from tearing the top of the liner. The arms 122 carrying the folding plates 120, 121 are mounted to turn freely upon studs 128 in brackets 129 forming part of the machine frame, and the movement of the arms to perform the folding operation is effected by a cam 130 through two sets of cam rolls 132, cam 70 arms 134, and connecting links 136, as illustrated in Fig. 11. During the operation of the mechanism, one folding plate is moved inwardly to substantially the center line of the liner and its edge serves as a folding edge over which the upstand- 75

ing sealed portion of the mouth of the liner may be folded during the subsequent inward movement of the remaining folding plate so that in this manner the upper or sealed portion of the liner may be folded down into a position such as to permit the top flaps of the outer carton to be subsequently closed.

After the described folding operations have been performed by the mechanisms illustrated in Fig. 11, the carton moves through stations 7 and 8, and during the movement into station 7, see Fig. 1, provision is made for turning the pocket 23 holding the carton through 90° in order to present the projecting and flattened down end flaps 140, see Fig. 30, of the liner to the operation of an additional set of folding members 142, 143 which are arranged to operate transversely of the line of travel of the carton, and as illustrated in Fig. 13, the mechanism for effecting the rotation of the carton during movement from station 6 to station 7 includes a pivotal mounting for the pocket 23, as best shown in detail in Fig. 14, and comprising a depending stud 146 secured to the bottom of the pocket 23 and by which the pocket is rotatably mounted upon a link 148 of the conveyor chain 24. The stud 146 is arranged to project through the hole in the link and the projecting portion has mounted thereon a notched collar 149 secured to the link of the chain. A second collar 150 provided with projections is keyed to the stud 146 and is arranged to cooperate with the notched collar 149 to control and confine the rotary movement of the pocket to exactly 90°. A spring 152 is interposed between the bottom of the second collar 150 and a nut 153 screwed on the end of the stud. Each pocket 23 is provided with arms 154 projecting from two opposite corners thereof, and having rollers 156, as illustrated in Fig. 13. One of the rollers 156 is adapted to engage an abutment or bracket 158 secured to the machine frame during the movement of the pocket 23 into station 7 and to thereby effect a turning movement of the pocket through exactly 90°. After the folding operations to be described are performed at station 7, provision is made during the movement of the pocket into station 11 for effecting an additional turning movement in the reverse direction to restore the pocket to its original position occupied when in station 6.

Referring now to Figs. 24-33, it will be observed that when the pocket and carton are in station 7, the upper portion of the liner will occupy the position illustrated in Fig. 30 with the sealed portion of the bag flattened down and the ends 140 thereof projecting outwardly beyond the ends of the carton. Provision is made while the package is in station 7 for folding inwardly the flattened and projecting triangular end portions 140 of the liner, and as illustrated in Fig. 12, a folding mechanism is provided which in construction and operation is a duplicate of folding mechanism illustrated in Fig. 11, for folding down the sealed mouth of the inner bag, as above described. As illustrated in Fig. 12, the folding mechanism includes folding plates 142, 143, which are arranged to move in under the ends of the flattened triangular ends 140 of the inner package and to fold the same inwardly into a position such as is shown in Fig. 31. The cams 174 for actuating the swinging folding plates are timed so that the folding operations take place one after the other.

After the package has moved into station 8,

provision is made for folding down the two end flaps 180, 181 of the carton. As illustrated in Fig. 19, this mechanism includes a swinging folding member 184 mounted upon the end of an arm 186 comprising one arm of a bell-crank 187, pivoted on a stud 188 secured in a bracket 189, forming part of the machine frame, and the arm 186 is arranged to be moved by a cam 192 on the cam shaft 30 through a cam roll 186, cam arm 186, connecting link 188, and through 10 the second arm 189 of the bell-crank 187. The inward movement of the folding member 184 operates, as will be apparent from an inspection of Fig. 19, to fold inwardly one of the end flaps 180, 181, and during the advance of the package 15 as it leaves station 8 the remaining flap is folded in by a top and stationary folding plate 201. The cam 192 is so designed as to continue the movement of the folding member 184 to hold down the previously folded flap until the second end 20 flap has been folded by the plate 201 into a position to retain both flaps.

During the movement from station 8 to station 9, the projecting side flaps of the carton are passed between glue rolls 204 supplied with glue 25 from any convenient source of supply as from the glue pots 206, the details of construction and mode of operation of which are well-known in this art and need no further description. After the application of adhesive to the exposed upper 30 surfaces of the extended flaps, as illustrated in Fig. 20, the continued movement of the carton through station 9 is utilized through the fixed folding plates 208, 209 to turn over the two side flaps of the carton in succession and thereby 35 place the carton in a condition so that when it arrives at station 10 a cam operated presser 210 may operate to press down and seal the top flaps of the carton. As illustrated in detail in Fig. 22, this presser includes a presser member 40 211 arranged to slide vertically in a bracket 212 forming a part of the machine frame, and an actuating cam 214 upon the cam shaft 30 operates through a cam roll 215 and cam arm 216, and a pivotally connected connecting rod 218 to 45 effect reciprocation of the presser member 211 to perform the pressing operation. Thereafter the closed and sealed carton is moved into station 11 where a reciprocatory pusher member 220 operates to push it from the pocket 23 laterally onto a discharge conveyor 222 by which it is 50 conveyed from the machine. The pusher member 220 is arranged to slide in a guide 224 being actuated by a cam 226 through a three-arm lever 228, the third arm of which is connected by a 55 spring 229 to retain the cam roll 230 in engagement with the cam 226 and which also functions to perform a resilient ejecting operation and to permit the cam to return the parts after each ejecting operation.

In order to adapt the machine for the manufacture of sealed containers from paper or other material coated with paraffin or similar moisture-proof material, provision is preferably made for removing the paraffin or other coating material 65 from those portions of the material which are to form the inside of the mouth of the container to the end that a most efficient and satisfactory seal may be obtained, preferably by folding outwardly those portions of the bag or other container to 70 thereby enable the two halves of the container to be brought together and sealed with a paper to paper contact extending entirely across the mouth of the container. In the illustrated machine provision is made for removing the mar- 75

ginal portions of the paraffin or other coating material from the web as it is drawn from the supply roll 18 and prior to its presentation to the mechanism for forming the lining. As herein shown in Figs. 1, 4, 5 and 6, this mechanism may comprise two pairs of electrically operated heating elements 240, 242 of any usual or preferred construction and which are designed to contact with the opposite surfaces of two marginal portions of the web as the latter is drawn between such heating members. Referring now to Figs. 4, 5 and 6, one set of heating plates 240 are mounted upon a bracket 246 secured to the frame of the machine and the other pair of heating plates 242 are mounted upon a crossbar 248 secured to the bracket 246 through bolts 250. The crossbar 248 and the heating plates 242 are yieldingly urged toward the heating plates 240 and into yielding engagement with the web passing between the plates by springs 256 encircling the bolts, as shown in Fig. 4. With this arrangement, during the operation of the machine, as the web is drawn from the supply roll 18, the paraffin or other waterproof coating material is melted as the web is drawn between the heating plates and the amount of paraffin or other coating along the marginal portions of the web is reduced sufficiently so as to enable a paper to paper contact to be secured when the mouth of the bag is subsequently closed and sealed in the manner previously described.

For some purposes I may prefer to remove the paraffin or other coating from one surface only of the web as it is drawn from the supply roll 18, and as illustrated in Fig. 1 an idler roll 260 may be used in conjunction with a single pair of heating plates 242.

If found advantageous, the modified form of mechanism illustrated in Fig. 34 may be employed for removing the paraffin from one or both surfaces of the paraffin coated web as it is drawn from the supply roll 18, and as illustrated therein, the web is caused to pass between a pair of heating rolls 270 by which the paraffin coating is melted along the desired marginal edges of the web, and thereafter the web is caused to come in contact with movable absorbent members 272 by which the molten paraffin may be absorbed to be removed from the web. As illustrated in Fig. 34, the movable absorbent members 272 comprise fibrous absorbent belts arranged to run around a series of guide rolls 274 and through a tank 276 which may contain a bath of solvent for the paraffin or other coating. As the web is drawn upwardly from the solvent bath within the tanks 276, it is caused to pass through squeeze rolls 278 for removing the solvent and rendering the belts 272 again highly absorbent as they come in contact with fresh portions of the web from which molten paraffin is to be removed. The belts 272 are preferably arranged to be driven through suitable mechanism, not shown, in timed relation to the movement of the web. As used throughout the claims, the term "longitudinal axis of the containers" is intended to define the major axis of the container, and in the machine means are provided for effecting the rotation of the container about the longitudinal axis thereof for the purpose of presenting different sets of flaps at the same end of the container to the operation of succeeding folding instrumentalities.

By the terms "paraffin" and "paraffin paper" as used throughout the specification and claims hereof, I intend to include various coating materials and various saturated or coated papers

or webs all of which are characterized by the difficulty or inability of obtaining satisfactory adhesion with glue or similar adhesives, and while in the illustrated machine heating plates have been illustrated for the purpose of removing the paraffin, it will be understood that other means may be employed if found advantageous, particularly in those instances where other types of coating or saturating materials instead of paraffin are employed.

While the preferred embodiment of the invention has been herein illustrated and described, it will be understood that the invention may be embodied in other forms within the scope of the following claims.

Having thus described the invention, what is claimed is:—

1. In a machine of the character described, in combination, container forming means, means for supplying paraffin paper to the container forming means to form the container, means for removing portions of the paraffin from the material being supplied to the container forming means, means for securing said container, and means for closing and sealing the mouth of the container, said paraffin removing means operating to enable the production of a paper to paper contact between the contacting portions of the mouth of the container to be sealed.

2. In a machine of the character described, in combination, container forming means, means for supplying paraffin paper to the container forming means, paraffin removing means operating to provide a container having a sealing rim at the inside of the mouth thereof substantially free from paraffin, container filling means, container closing means, container sealing means, said closing and sealing means being operative to produce a complete seal across the entire mouth of the container.

3. In a machine of the character described, in combination, means for supporting a supply roll of paraffin paper, means for withdrawing paraffin paper from the supply roll, means for forming a length thereof into a container, container filling means, means operative upon the paraffin paper prior to its formation into the container for removing paraffin from the portions of the paper which are to form the upper portion of the inside of the mouth of the container, means for thereafter pressing together the two opposite walls of the mouth portion of the bag to provide a continuous paper to paper contact across the entire mouth of the container, and means for adhesively affixing together the contacting portions of the mouth of the container.

4. In a machine of the character described, in combination, container forming means, means for supplying paraffin paper to the container forming means, means for removing portions of the paraffin from the material being supplied to the container forming means whereby in the formed container the upper portion of the inside of the mouth of the container is rendered substantially free from paraffin, container filling means, means for adhesively affixing together the two opposite walls of the mouth portion of the container to provide a continuous seal across the entire mouth of the container.

5. In a machine of the character described, in combination, container forming means, means for feeding a web of paraffin coated paper to the container forming means, means for removing paraffin from the portions of the paper which

are to form the upper portion of the inside of the mouth portion of the container, said means including means for heating the paraffin, a movable member adapted to engage said portions of the web to convey paraffin therefrom, and means for removing the paraffin from said member, container filling means, means for adhesively affixing together the two opposite walls of the mouth portion of the container to provide a continuous paper to paper contact across the entire mouth of the container.

6. In a machine of the character described, in combination, container forming mechanism, means for supplying a paraffin coated sheet to the container forming mechanism, means for removing paraffin from the portions of the sheet which are to form the upper portion of the inside of the mouth of the container, said means including a movable absorbent member and a solvent tank for removing the absorbed paraffin from said member.

7. In a machine of the character described, in combination, means for forming a container having an open end from paraffin coated paper, container filling means, means for closing said open end with a paper to paper contact including paraffin removing means operated to provide the container with an uncoated sealing rim around the interior of the mouth thereof, and mechanism for continuously taking away the paraffin thus removed from the mouth of the container, and means for sealing the contacting portions of the mouth of the container.

8. In a machine of the character described, in combination, a conveyor provided with a plurality of container holding devices rotatably mounted thereon, folding instrumentalities for folding the flaps of a container supported by said devices, and means for effecting the rotation of said holding devices and the containers supported thereby about the longitudinal axis of the containers to thereby present different sets of flaps at the same end of the container to the operation of succeeding folding instrumentalities at different stations in the movement of said conveyor.

9. In a machine of the character described, in combination, a conveyor provided with container holding devices rotatably mounted thereon, folding instrumentalities, and means for rotating the container about its longitudinal axis to present different sets of flaps at the same end of the container to the operation of successive folding instrumentalities.

10. In a machine of the character described, a conveyor provided with a plurality of container holding devices, folding instrumentalities, and means for effecting rotation of the container about its longitudinal axis to present different sets of flaps at the same end of the container to the operation of successive folding instrumentalities.

11. In a machine of the character described, in combination, supporting and conveying means for a plurality of containers, folding instrumentalities, and means for effecting rotation of said containers about their longitudinal axes to present different sets of flaps at the same end of the container to the operation of successive folding instrumentalities.

12. In a machine of the character described, in combination, an endless conveyor provided with a plurality of spaced pockets rotatably

mounted thereon for operatively supporting containers, a plurality of folding instrumentalities located at successive stations along said conveyor, means for rotating successive pockets about their longitudinal axes during movement from one set of folding instrumentalities to a succeeding set.

13. In a machine of the character described, in combination, a conveyor provided with a plurality of spaced container holding members rotatably mounted upon the conveyor, end flap folding means, side flap folding means, and means for rotating the container holding members about their longitudinal axes for the purpose specified.

14. In a machine of the character described, in combination, container supporting means, means for folding outwardly two opposed portions of an open end of the container, means for pressing together the remaining two opposite walls of said end of the container to provide a continuous contact across the entire end of the container, and means for applying adhesive to the inner surface of said walls of the container.

15. In a machine of the character described, in combination, container supporting means, means for folding outwardly two opposed portions of an open end of the container, means for pressing together the remaining two opposite walls of said end of the container to provide a continuous contact across the entire end of the container, means for applying adhesive to the inner surface of said walls of the container, and means for thereafter folding down the sealed portion of the mouth of the container.

16. In a machine for closing a lined carton, in combination, carton supporting means, means for folding outwardly the closed end portions of the liner, means for applying adhesive to the inner surfaces of the two opposite portions of the mouth of the liner which are to contact, means for pressing together and adhesively affixing the two opposite portions of the mouth of the liner to provide a continuous seal across the entire mouth of the liner, means for thereafter folding down the sealed mouth portion of the liner, and means for thereafter closing and sealing the top flaps of the carton.

17. In a machine of the character described, in combination, container forming means, paraffin removing means cooperating with the container forming means to produce a container having the paraffin removed from the inside of the mouth thereof, container filling means, container closing mechanism, and container sealing mechanism, including adhesive applying means, said closing and sealing mechanism being operative to bring together and seal the two opposite walls of the mouth of the container with a paper to paper contact.

18. In a machine of the character described, in combination, container forming means, paraffin removing means cooperating with the container forming means to produce a container having the paraffin removed from the inside of the mouth thereof, container filling means, container closing mechanism, and container sealing mechanism, said closing and sealing mechanism being operative to bring together and seal the two opposite walls of the mouth of the container with a paper to paper contact, including adhesive applying means, and means for thereafter folding down the sealed portion of the mouth of the container.

19. A machine for producing a lined carton having, in combination, means for forming the lining from paraffin paper, means for introducing the formed lining into a carton, paraffin removing means cooperating to produce a liner having the paraffin removed from the inside of the mouth thereof, container filling means, means for sealing together two opposite walls of the mouth of the liner from which the paraffin has been removed, including adhesive applying means, means for folding down the sealed portion of the liner, and means for thereafter closing and sealing the top flaps of the carton. 5

STANLEY R. HOWARD.
